UNITED STATES PATENT OFFICE.

PETER P. FINDLAY AND ANGUS McINNIS, OF DONALD, BRITISH COLUMBIA,
CANADA.

APPARATUS FOR OPERATING PUMPS.

SPECIFICATION forming part of Letters Patent No. 363,617, dated May 24, 1887.

Application filed March 14, 1887. Serial No. 230,764. (No model.)

To all whom it may concern:

Be it known that we, PETER PRESTON FINDLAY, carpenter, and ANGUS McINNIS, carpenter, both of the town of Donald, in the district 5 of Kootenay, in the Province of British Columbia, Canada, have jointly invented certain new and useful Improvements in Apparatus for Operating Pumps, of which the following is a specification.

10 The object of the invention is to construct a machine so that with a small amount of leverage to contend with a much longer stroke may be attained than is possible by the crank principle of attaining length of stroke. For 15 instance, to attain a fifteen-inch stroke in the usual way by the crank principle, the connection with crank would have to be seven and one-half inches off the center, and the leverage to contend with would be seven and one-half inches, while the wholesweep of the crank 20 would be 47.2 inches. By the reacting principle demonstrated by this invention to attain the same length of stroke—viz., fifteen inches—by one full revolution of the driver, 25 it is only necessary to have a wheel fifteen inches in circumference, 4.75 inches in diameter, or 2.37 inches radius. Consequently, in 30 this instance we can attain the same length of stroke, fifteen inches, while the leverage to contend with is only 2.37 inches. Here the 35 wheel makes a full revolution and the slide runs from end to end. When the slide connected with the piston runs only half-way, returning in its movement at the half-circumference of the cog-wheel, to attain the same 40 length of stroke—viz., fifteen inches—it is necessary to have a wheel of sufficient diameter to give thirty inches of circumference—i. e., a diameter of nine and one-half inches or four 45 and three-fourths inches radius—so that in this instance the leverage to contend with is four and three-fourths inches. To produce this movement it is necessary that an inclined plane should be placed in the middle of the 50 slide, as indicated at W.

This device or invention is peculiarly adapted for pumps used for mining purposes, where a long slow stroke is required, while the leverage to be contended with, as before indicated, will be but small.

Figure 1 is a perspective view of the ma-

chine, showing the relative positions of the various parts at the beginning of a stroke. The spindle instead of being vertical, as shown in the drawings, may be horizontal or in any other position. In this view the frame is partially broken away to exhibit the peculiar construction. Fig. 2 is a detail of the slide, (which gives motion to the pump-piston,) showing racks on different planes on which 60 the cog-wheels work, and also showing the inclined planes placed there for the purpose of throwing the cog-wheels into and out of gear with the circular disks, as hereinafter explained, and also showing the plates on which 65 the recessed parts or lips of the drivers work. Fig. 3 is a section through a b in Fig. 1. Fig. 4 are details of the cog-wheels and the two circular disks or flanges which engage with the said cog-wheels, all of which work on the spindle or shaft which is actuated by the driving power. Fig. 5 is the under face of the upper cog-wheel in Fig. 4, showing the metal ring which is placed under the hook-shaped lugs shown on the lower cog-wheel in Fig. 4, before 70 the spindle is passed through the flanges and cog-wheels, and indicating the means of connecting the two cog-wheels, so as to enable them to shift their position together at the beginning and end of each stroke, while also enabling them to revolve in a contrariwise direction on the spindle or shaft when the machine is in operation, as hereinafter explained. 75

Similar letters indicate similar parts in the various figures.

A in the drawings is the circular disk farthest from the power, and rigidly connected to the shaft D by key d, (vide Fig. 3,) and having a notch, C, cut out for the purpose of forming a shoulder against which the driver or pushing-arm E may engage, so that when the driver E becomes engaged in said notch C and against said shoulder the cog-wheel F partakes of this motion of the circular disk A, and drives the slide which actuates the piston. 90 Said driver E is rigidly fastened on the cog-wheel F, or is cast in one piece therewith, and the end thereof has lips or a hollowed-out portion, f, which engages with the side plate, p, at the proper time in the course of the revolution of said cog-wheel F, for the purpose of 95 keeping the two cog-wheels F and G in their 100

proper relative position on the shaft when the machine is in operation. The end of said cog-wheel F has a hub or hollow axle, which fits into a circular recess in said circular disk A, 5 and is not rigidly attached to said shaft D. Both of the cog-wheels have teeth varying in number according to the circumference of the cog-wheels, which cog-wheels engage in their respective racks R R', which are placed in the 10 slide S on different planes and on opposite sides thereof, and should contain at least one more tooth than in the periphery of the cog-wheels. The cog-wheel G is of a construction similar to F, and said cog-wheels are connected 15 together back to back, as shown by Figs. 4 and 5.

g is a metal ring fastened to cog-wheel, and h h are hook-shaped lugs which rest on said ring g. This cog-wheel G, like cog-wheel F, 20 is not rigidly attached to the shaft D, but said shaft passes through both it and the adjoining cog-wheel, on which shaft they move in a direction always opposite to one another when the machine is working, while at the same 25 time they can move together along the shaft, by reason of their connection by the ring g and lugs h h, when the drivers E and M engage with the shoulders in the notches C C'; and as the cog-wheels F and G come in gear and 30 partake, respectively, of the motion of the adjoining circular disks A and T, the said cog-wheels are thrown into and out of gear by reason of the drivers E and M working up the inclined planes at the beginning and end of each stroke, 35 and by moving the cog-wheels along the shaft one driver is disengaged or lifted from its notch in its adjoining circular disk, thus leaving this other cog-wheel free to revolve back, partaking of the motion of the slide S, while the other 40 driver at the same time is moved into and engages in the notch of its adjoining circular disk, and so the cog-wheel of which it forms a part partakes of the motion of its adjoining circular disk and moves the slide forward or 45 backward, as the case may be, in the stroke. This cog-wheel G has a hub or hollow axle similar to cog-wheel F, and which works in the circular recess in the circular disk T, and has a pusher or driver, M, with lips or hollowed 50 portion k, which engages with the supporting-plate q during a portion of the revolution for the purpose of keeping the cog-wheels F and G in their proper position on the shaft D.

The circular disk or flange T is similar in 55 construction to A, with circular recess for the hub of cog-wheel G, and has a notch, C', and faces the other disk, A, as shown. It is rigidly attached to the shaft D by being keyed thereon by the key e, as shown in Fig. 3, or in 60 any other suitable way, and is so placed on the shaft (vide Fig. 3) as to allow of a sufficient movement of the cog-wheels F and G along the shaft or spindle D for one driver to clear its adjoining circular disk while the 65 other driver is engaged against the shoulder in the notch of its adjoining disk, and thus by means of the cog-wheel, of which the latter

driver forms a part, gives motion to the slide S. Only one of these drivers is engaged at one time, while the other is moving around in 75 an opposite direction until it reaches the top or bottom of the slide, as the case may be.

D is the shaft or spindle, to which the circular disks are attached rigidly in such a position that the notches C C' or shoulders are 75 opposite to one another, or at about a one-half revolution or circumference of the disk. The cog-wheels F and G also revolve on said shaft, as described, and said shaft rests and works in bearings in the frame-work of the machine, 80 as shown in Fig. 3 at K K', and is connected with the driving power at P.

The slide S (vide Figs. 1 and 2) works in suitable grooves, Q Q', in the frame-work of the machine and contains the racks R R', the 85 teeth of which mesh with the teeth on the cog-wheels F and G, and are placed opposite to one another on the slide and at different planes, so as to engage with the teeth of their respective cog-wheels. These racks and teeth are 90 sufficiently wide to allow for the shifting motion of the cog-wheels along the shaft as the drivers or pushers E and M are moved into or out of gear with their respective circular disks A T. The teeth on these racks are directly opposite 95 to each other.

x and y are the inclined planes placed in the positions shown in the drawings, which the drivers E and M mount at the commencement and end of each stroke, thus alternately causing a driver to engage with the notch in its adjoining circular disk and cause the cog-wheel to receive its motion and push the slide S forward in its stroke, while at the same time the other driver is moved out of its notch in 105 its adjoining disk, and the cog-wheel of which this latter driver forms a part then partakes of the motion of the slide S and revolves around the shaft in a direction contrary to the other cog-wheel until the other end of the stroke is 110 attained, when its driver mounts in turn the inclined plane at the end of the slide, engaging in 115 its circular disk and releasing the other driver from its notch in its circular disk, so that the former driver, engaging in 120 the notch of its adjoining disk, causes its cog-wheel to work the slide back again on its stroke by meshing with its rack, while the other cog-wheel, being freed from its circular disk, moves around the shaft in a direction 125 contrary to its adjoining cog-wheel, and has motion communicated to it by the slide until the end of the backward stroke is attained, when the process is repeated, and thus the reciprocating motion of the slide which actuates 130 the piston is kept up.

All parts of the gearing, shafting, cog-wheels, &c., must of course be kept properly lubricated, so as to reduce friction as far as possible and insure the easy working of the various parts.

When the slide runs only half-way, returning in its movement at the half-circumference of the cog-wheel, as before indicated, an in-

clined plane, W, should be placed half-way on the rack, as shown in Fig. 2.

Fig. 1 shows the machine complete and in operation just at the commencement of a stroke. The driver M has just mounted the inclined plane y, and has engaged with the notch C' in the circular disk T, which has a motion, as indicated by the arrow-head, and the motion of the cog-wheel G has just been reversed, as indicated by said arrow-head, partaking of the motion of said disk T, and is moving the slide S forward in its stroke, as shown by arrow-head. At the same time the other cog-wheel, F, has just been moved out of its notch C and has commenced to move clear of its adjoining disk, A, in a direction opposite to what it has just had when its pusher was engaged in its notch C. Its present motion is indicated by the arrow-head. The lips f on the said driver E are moving forward, as indicated by the arrow-head, to meet plate p, so that by the time the driver M has revolved round clear of the side of slide the said pusher E, working on the plate p, will be in a position to keep the cog-wheels in place and the pusher M in its notch C'. By the time the lips f have revolved around free of plate p the lips k on pusher M will have met the opposite plate, q, and engaged with it, still keeping the cog-wheels in position and the driver M in its notch C'. By the time driver M has sufficiently revolved around to clear side plate, q, the end of the stroke is attained and the cog-wheels drop or are pushed into position by the inclined plane x, releasing the pusher on cog-wheel G from its notch C' in the circular disk T, while the other driver, E, on cog-wheel F becomes engaged in the notch C of the disk A, and the motion of the cog-wheels F and G becomes reversed, thus driving the slide S on its return stroke and communicating to the slide a reciprocating motion. On the return stroke the lips of the drivers E and M do not engage with the side plates, p and q.

On the driving shaft or spindle D may be placed a ratchet-wheel, N, and a pawl, n, attached to the frame of the machine in order to prevent reflex action, the proper direction of the motion of said shaft being the same as the hands of a watch.

What we claim as our invention is—

1. The cog-wheels F and G, connected together by ring g and hook-shaped lugs h h, the circular disks A and T, having notches C C', the

drivers E and M, which drivers have lips f and k formed to move on side plates, p and q, said cog-wheels and circular disks being placed on the shaft D, in combination with the racks R R' in the slide S, working in proper bearings, said slide having also formed thereon the inclined planes x and y, in the manner and for the purpose specified.

2. The cog-wheels F and G, connected together by ring g and hook-shaped lugs h h, the circular disks A and T, having notches C C', formed thereon, the drivers E and M, which drivers have lips f and k formed to move on the side plates, p and q, as described, said cog-wheels and circular disks being placed on the shaft D, ratchet-wheel N, and pawl n, in combination with the racks R R' in the slide S, working in suitable bearings, said slide having also formed thereon the inclined planes x and y, for the purpose of throwing said cog-wheels into and out of gear with said circular disks, as specified.

3. The cog-wheels F and G, connected together by ring g and hook-shaped lugs h h, the circular disks A and T, having notches C C', the drivers E and M, having the lips f and k and plate p, the shaft D, the ratchet-wheel N, and pawl n, in combination with the racks R R' in the slide S, which works in suitable bearings, having inclined plane x and inclined plane W, the latter being formed at the middle of the slide, as indicated, and for the purposes specified.

4. The combination, with two cog-wheels connected together and a central shaft around which said wheels are adapted to revolve in opposite directions, of a ratchet-wheel and pawl constructed to prevent reflex action of said shaft, two disks rigidly connected to said shaft and provided with notches, drivers on said cog-wheels engaging said notches and provided at their ends with lips, side plates with which said lips engage, a slide which gives motion to the piston, inclined planes formed on said slide, and racks set on different planes in said slide and engaging the cog-wheels, all substantially as and for the purpose specified.

Donald, British Columbia, February 24, 1887.

PETER P. FINDLAY.
ANGUS MCINNIS.
